UNITED STATES PATENT OFFICE

JOHN E. H. RANDERSON, OF ALBANY, NEW YORK

PACKAGE OF TOILET PAPER

Application filed October 19, 1928. Serial No. 313,539.

The usual practice in packaging toilet paper in rolls is to supply the paper in a single, continuous web or strip which is perforated or weakened, at regular intervals, and wound

5 upon a hollow tube.

Where toilet paper is packaged in separate pieces which are interfolded for use in wall cabinets, double instead of single sheets are interfolded in such a way that two sheets

10 are pulled together from the cabinet, thus automatically providing the consumer with the double thickness of paper usually desired. Where paper is furnished in roll form of

15 the ordinary type, it is usual to tear at least two sheets together from the roll and there-

after fold one over the other before using.

The object of my invention is to provide a package of toilet paper in rolled form and of such character that the necessity of overfold-

20 ing the sheets to obtain the desired thickness, after tearing them from the roll is entirely eliminated.

With this object in view my invention consists of a roll or package of the type described

25 below and illustrated in the accompanying drawings.

Referring to the drawings, 1 represents the usual hollow tube upon which the paper, 2, is rolled. Instead of rolling a single strip

30 or web of paper upon the tube, 1, I propose to roll two or more webs or strips together thereon. In the drawing I have illustrated only two separate strips, such as 3 and 4, but it is to be understood that while this is the

35 preferred form, my invention, in its broadest aspects, contemplates the rolling of any number of strips or webs together.

Each strip is provided with transverse lines of weakness, preferably perforations, which

40 are spaced at regular intervals as shown at 5, on the top sheet, and at 6, on lower sheet. These lines of weakness are designed to come substantially together as shown in the drawing, so that instead of a single sheet being

45 torn from the roll two sheets are grasped at once and torn together.

It is to be understood, of course, that the weakened portion, 5, in the upper web of paper need not be precisely over the weakened

50 portion, 6, in the lower web, but, on the other

hand, these perforations should be reasonably close together so that the sheets, such as 7 and 8, when torn together from the roll, will be substantially coextensive.

What I claim is—

A toilet paper package comprising a plurality of lengths of paper wound together to form a roll, each length being provided with spaced, transverse lines of weakness, and the lines of weakness in the outer layer of paper coinciding substantially with the lines of weakness in the under layer of paper whereby a plurality of substantially coextensive sheets may be torn from the roll in one operation.
